Large Cable File Bag with Shoulder Strap—by Loudmouth, 80 ratings, Manufacturer: JOLMER Pty Ltd, ASIN: B07WW4HTLT, online on Amazon.com, Date First Available: Dec. 23, 2019.*

Primary Examiner — Elizabeth A. Albert

(74) Attorney, Agent, or Firm — Eric Karich; Karich & Associates

(57) **CLAIM**

The ornamental design for a cable file bag, as shown and described.

DESCRIPTION

FIG. 1 is a perspective view of a cable file bag, in an open configuration, showing my new design;

FIG. 2 is a perspective view of the cable file bag, in a closed configuration, showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The cross-hatching pattern, although shown intermittently, is understood to be distributed uniformly across the surface.

1 Claim, 5 Drawing Sheets
